COIN HOLDER OR SIMILAR ARTICLE

Albert Rothgart, Brooklyn, and Theodore Mehrer, Scarsdale, N.Y., assignors to Visionade Manufacturing Co., Inc., Brooklyn, N.Y., a corporation of New York

Filed May 18, 1962, Ser. No. 70,188

Term of patent 7 years

(Cl. D87—3)

FIG. 1

FIG. 3

FIG. 2

FIG. 4

FIG. 5

FIG. 6

FIG. 1 is a top plan view of a coin holder showing our new design;

FIG. 2 is a front elevational view;

FIG. 3 is a left side elevational view;

FIG. 4 is a right side elevational view thereof;

FIG. 5 is a bottom plan view; and

FIG. 6 is a rear elevational view.

My design comprises a block of resilient material in the shape of an animal figure having a series of visible serrated slits in the body portion thereof, said slits adapted to receive and hold coins and the like substantially as shown.

We claim:

The ornamental design for a coin holder or similar article, substantially as shown and described.
